UNITED STATES PATENT OFFICE

2,442,963

AIR DISTRIBUTING UNIT

Henry R. Sewell, Norwell, and Robert T. Palmer,
Sharon, Mass., assignors, by mesne assignments,
to Westinghouse Electric Corporation,
a corporation of Pennsylvania

Application March 31, 1945, Serial No. 585,890

2 Claims. (Cl. 98—38)

1

This invention relates to air distributing units in which conditioned air from a central source is supplied under pressure, and in which the conditioned air induces the flow of air recirculated from the space served.

The Cano Patent No. 1,995,667 and the Keyes Patent No. 2,000,597 disclose air distribution units in which conditioned air from a central source is passed through ejector nozzles for inducing the flow of recirculated air through inlets in the sides of the units, and in which the mixed recirculated and conditioned air is discharged through outlets in the tops of the units. A disadvantage of such units is that they were designed primarily for air cooling, and do not provide proper distribution when the conditioned air is heated air. With such units the heated air is projected vertically upwards, overheating the ceiling space.

This invention provides a local distribution unit of the type disclosed by said patents but differs therefrom by including provisions for drawing in recirculated air through the top of the unit, and for discharging the mixed recirculated and conditioned air from a vertical side of the unit, in the heating season.

An object of the invention is to improve the distribution of heated air from local distribution units, supplied with conditioned air from a central source.

The invention will now be described with reference to the drawing, of which:

Fig. 1 is a side elevation with a portion of the front side removed, of an air distributing unit embodying this invention;

Fig. 2 is a sectional view along the lines 2—2 of Fig. 1;

Fig. 3 is a sectional view along the lines 3—3 of Fig. 1, and

Fig. 4 is an enlarged, projected view of the slide adjusting mechanism used.

The unit has the conditioned air pressure chamber 10 into which conditioned air is supplied through the duct 11 from a central source such as that disclosed in said Cano patent. The chamber 10 has the inner vertical wall 12 having the spaced perforations 13 therein, and has the upper wall 14 with the spaced nozzles 15 formed therein.

The plate 16 with the perforations 17 corresponding in number, spacing and size to the nozzles 15, is slidably supported between the horizontal flanges 18 at the opposite ends of the unit, and contacts the underside of the wall 14.

The plate 19 with the nozzles 20 formed therein, and which correspond in number, spacing and size to the perforations 13 in the wall 12, is slide-

2

bly supported between the vertical flanges 21 at the opposite ends of the unit, and contacts the outer side of the wall 12.

The knob 22 at the front side of the unit, is connected to the rod 23 which in turn, is connected to the extension 24 of the plate 16, and serves to slide the plate 16, when pulled forward, from the position shown by Fig. 2 where the inlets of the nozzles 15 are in alignment with the perforations 17 in the plate 16, to a position where the nozzles 15 and the perforations 17 are out of alignment.

The lugs 25 on the underside of the plate 16 are pivoted to the links 26 at the opposite ends of the unit. The links 26 are connected to the links 27 which are pivoted to the lugs 28 on the outer side of the plate 19. The links 26 and 27 are rotatably supported on the shafts 29 which extend inwardly from the ends of the unit.

When the plate 16 is moved as previously described, for moving the perforations 17 out of alignment with the nozzles 15, the plate 19 is moved upwardly by the described mechanism including the links 26 and 27, from the position shown by Fig. 4 where the nozzles 20 are out of alignment with the perforations 13, to a position where the nozzles 20 and the perforations 13 are in alignment.

Thus when the knob 22 is in the position shown by Fig. 2, the upper nozzles 15 and the upper perforations 17 are in alignment, and the side nozzles 20 and the side perforations 13 are out of alignment, and when the knob 22 is pulled forward, the upper nozzles 15 and the upper perforations 17 are placed out of alignment, and the side nozzles 20 and the side perforations 13 are placed in alignment.

The grille 30 is alongside the nozzles 20, and serves as a recirculated air inlet grille in the cooling season, and as an air discharge grille in the heating season as will be described.

The upper grille 31 is in the top of the unit, and serves as a discharge grille in the cooling season, and as a recirculated air inlet grille in the heating season as will be described.

In the cooling season when chilled, dehumidified air is supplied through the duct 11, the knob 22 is positioned as illustrated by Fig. 2 whereby the nozzles 15 and the perforations 17 are in alignment, and the nozzles 20 and the perforations 13 are out of alignment. The conditioned air passes from the chamber 10 through the perforations 17 and the nozzles 15, and induces the flow of recirculated air through the grille 30, and the mixed conditioned and recirculated air is

discharged from the grille 31 as disclosed by said patents. The continuous arrows indicate the air flow at this time.

In the heating season when heated, humidified air is supplied through the duct 11, the knob is pulled forward away from the front side of the unit causing the nozzles 15 and the perforations 17 to be placed out of alignment, and the nozzles 20 and the perforations 13 to be placed in alignment. The conditioned air then passes from the chamber 10 through the perforations 13 and the nozzles 20, and induces the flow of recirculated air through the upper grille 31, and the mixed, recirculated air and conditioned air is discharged from the lower grille 30. The dash-dot arrows indicate air flow at this time.

The conventional heat exchanger 32 is located between the grilles 30 and 31, and serves as is usual, to change the sensible heat of the air passing over its surface if that is necessary.

Units embodying this invention may be supplied with conditioned air through small ducts or pipes as disclosed in the A. J. Lawless Patent No. 2,159,276, the recirculation taking place at the local units whereby there is no need for the ducts for conveying recirculated air back to the central conditioner.

While one embodiment of the invention has been described for the purpose of illustration, it should be understood that the invention is not limited to the exact apparatus and arrangement of apparatus illustrated, as modifications thereof may be suggested by those skilled in the art without departure from the essence of the invention.

What is claimed is:

1. An air distributing unit having an upper opening and a lower opening; a first ejector nozzle placed to discharge towards said upper opening; a second ejector nozzle placed to discharge towards said lower opening; means for directing conditioned air supplied from a central source, into said nozzles, and means for rendering said first nozzle ineffective and said second nozzle effective, whereby the flow of conditioned air through said second nozzle induces the flow

of recirculated air through said upper opening into said unit, and causes the mixed recirculated and conditioned air to be discharged through said lower opening, and alternatively rendering said first nozzle effective and said second nozzle ineffective, whereby the flow of conditioned air through said first nozzle induces the flow of recirculated air through said lower opening into said unit, and causes the mixed recirculated and conditioned air to be discharged through said upper opening.

2. An air distributing unit having an upper opening and a lower opening, a first ejector nozzle placed to discharge towards said upper opening, a second ejector nozzle placed to discharge towards said lower opening, means for directing conditioned air supplied from a central source into said nozzles, and interconnected means for closing off the supply of air to one of said nozzles and for opening up the supply of air to the other of said nozzles, said unit having walls around and interconnecting said openings, whereby when said first nozzle discharges conditioned air towards said upper opening, air is induced to flow into said lower opening for mixture with the conditioned air, and when said second nozzle discharges conditioned air towards said lower opening, air is induced to flow into said upper opening for mixture with the conditioned air.
